GRINDING MACHINE COMPANY, OF SIOUX FALLS, SOUTH DAKOTA, A CORPORATION
OF SOUTH DAKOTA.

GRINDING-MACHINE.

No. 911,210.

Specification of Letters Patent.

Patented Feb. 2, 1909.

Application filed August 25, 1908. Serial No. 450,188.

To all whom it may concern:

Be it known that I, CONRAD M. CONRADSON, citizen of the United States, residing at Madison, in the county of Dane and State 5 of Wisconsin, have invented certain new and useful Improvements in Grinding-Machines, of which the following is a specification, reference being had therein to the accompanying drawing.

10 This invention relates to a grinding machine adapted for the grinding of glass bottle-necks and surfaces of other articles.

Among the objects of the invention, are the production of a grinding machine 15 equipped with a plurality of grinding mechanisms that finish their work *seriatim*; the centralizing of the interior surface of the article to be ground by provision of a special chuck member that engages a previously 20 formed chuck-engaging surface on the work; and a novel arrangement of cams and cam-actuated parts for actuation of the work-chuck, whereby, in connection with other movements of the work-chuck and of the 25 grinding tool, the ground surface is properly finished.

Referring to the accompanying drawings forming a part thereof, Figure 1 is a view, partly in elevation and partly in lengthwise 30 section, on a line corresponding to line 1—1 of Fig. 2; Fig. 2 is, in part, a top plan view of a machine designed to carry three grinding mechanisms, each comprising a work-chuck mechanism and a grinding tool mechanism, and the intermediate work-chuck 35 being removed for greater clearness. The figure is partly in horizontal section at a line corresponding to 2—2 of Fig. 1, for better illustration of one of the adjusting 40 mechanisms of one of the work-chucks. Figs. 3, 4 and 5 each shows a work-chuck adjusting cam, these cams being in different 45 positions to indicate different stages of each grinding operation; Fig. 6 is a front elevation of the adjusting mechanism of a work-chuck; Fig. 7 is a horizontal section thereof at line 2—2 of Fig. 1 or 7—7 of Fig. 6; Fig. 8 is a diagrammatic development of the cam groove of the cams shown in Figs. 50 3, 4 and 5; Fig. 9 is an enlarged sectional detail, at a line corresponding to 1—1 of Fig. 2, of the angular relation of the grinding pencil and surface being ground; and 55 of the chuck member that engages a chuck-engaging surface.

In the drawings, 1 indicates the main frame comprising parallel vertical side pieces and transverse connections. Drive shaft 2 extends transversely of the frame at the rear portion thereof, and is mounted in 60 side bearings 3. It is provided near each end with an eccentric 4. These are connected by eccentric straps 5 with transverse shaft 6 mounted on slide 7, which is mounted on the horizontal ways 8. Rotation of eccentric 4 reciprocates slide 7 which carries three tool spindles each comprising a tool spindle frame 9 provided with uprights 9^a the upper ends of which are formed with bearings 10 for the rotatable tool spindle 11 70 provided at its front end with chuck 12 to hold the grinding pencil 13. Each tool spindle 11 is conveniently provided with a fixed shell 11^a between opposed walls of bearings 10 and is rotated by a belt 11^b. 75

Shaft 2 is provided with a belt pulley 2^a for a belt 2^b, so that tool slide 7 may be reciprocated to move the pencil endwise, independently of the movements of the work-chuck. The grinding surface of each pencil 80 is cone-shaped.

In the main frame there is mounted a transverse drive shaft 15 provided with a belt pulley 16 for drive belt 16^a. Shaft 15 is also provided with a fixed gear 17 which 85 meshes with a gear 18 fast on a transverse shaft 19 journaled in the sides of the main frame above the transverse shaft 15. Shaft 19 is provided with a fixed gear 20 which meshes with a gear 20^a fast on a transverse 90 shaft 23 also journaled in the sides of the main frame. Shaft 23, between its ends, carries three cams, each of which is for effecting adjustments of the work-chuck whereby the work is fed or moved laterally 95 against the conical end 14 of pencil 13.

As the work-chucks, their adjustable supporting mechanism and cam connections are identical, description of one set will suffice for all, as follows:—Each cam 21 is splined 100 at 22 to the shaft 23 and provided with a cam groove 24 having a high point 25. Groove 24 receives a cam roll 26 on an end of cam lever 27 fulcrumed at 28 to the main frame and provided at its front end with an anti-friction roll which engages the lower end of a screw 30 provided with a vertical slot which receives a spline 31 in the adjustable work-chuck carrier 32 and prevents the screw from being turned therein. The 110

- under end 33 of the screw rests on, and the carrier and work-chuck frame and mechanism are supported on, cam roll 29, the carrier 32 being mounted in recess 34 formed 5 in the main frame at three sides of the carrier, which is provided with opposite lateral wings 35 that slide vertically in ways formed by offset walls of the main frame and detachable plates 35^a, the carrier being 10 raised by upward movement of the front end of cam lever 27 and falling by gravity so that the lower end of screw 30 always rests on the anti-friction roll 29. Screw block 32 is chambered for reception of a nut 36 on 15 screw 30, this nut being provided between its ends with a bevel gear 37. The opposite ends of nut 36 bear against opposed walls of the chamber of the carrier, and the bevel gear 38, mounted on a spindle 39 and provided exteriorly with a hand wheel 40, meshes with bevel gear 37, so that whenever desired, rotation of bevel gear 38 will turn bevel gear 37 and nut 36 and compel screw 30 to move endwise in block 32, although 20 itself non-rotatable. Consequently the work-chuck may be moved towards, against or away from the grinding pencil by manipulation of hand wheel 40. The purpose of 25 this adjustment is to adjust the work-chuck 30 and grinding spindle in correct relation one to the other, and also to compensate for wear of the grinding pencil.
- Carrier 32 supports the work-chuck frame 41 which is fast thereon. Frame 41 is provided, 35 with vertical uprights 41^a, the upper ends of which are provided with bearings 42 to support the rotatable work-chuck 43 within which the bottles or other work are held during the grinding operation.
- 40 The front end of the work-chuck is provided with an exteriorly threaded and thereby adjustable annulus 44, the inner wall of which is shaped to fit the previously formed chuck-engaging surface α of the 45 bottle α^1 . This annulus or its equivalent is an important feature of the chuck and of my invention, for the previously formed chuck-engaging surface of the bottle is concentric with the longitudinal axis of the 50 bottle-neck or interior surface to be ground, and consequently when the bottle or other work is rotated in the chuck, it rotates concentrically to the longitudinal axis of the surface to be ground, so that contact of the 55 work surface of the grinding pencil grinds the interior of the bottle-neck or other work concentrically to said axis and thereby adapts the bottle-neck or other article for proper reception of a properly ground 60 bottle-stopper.
- The peripheral wall of the work-chuck is slotted at 45 so that the bottle or work may be inserted and removed through these slots. The work-chuck is provided with a 65 slidably mounted, spring-pressed clamp 46

for holding the bottom of the bottle and pressing the bottle against the annulus 44, which is thus shaped to permit passage of the grinding pencil for contact with the interior surface to be ground. Clamp 46 is 70 provided with a spindle 47, and a coiled spring 48 is mounted around spindle 47, between the solid front end 49 of the chuck and the slidable clamp 46. The exterior of clamp 49 is formed as clutch member for co- 75 operation with clutch number 50 on the opposed end of belt pulley 51, which is rotated by a belt 52 and provided with a groove 53 for reception of an end of a bell-crank lever 54, pivoted at 55 to a projection 80 55^a of frame 41. The other end of the bell-crank lever is loosely jointed at 56 to a treadle-rod 57, the lower end of which is pivoted at 58 to treadle 59 pivoted at 60. When it is desired to retract clamp 46, in 85 order to remove or insert a bottle through a slot 45, the treadle is depressed and clamp 46 consequently retracted. When a fresh bottle is put in place, the treadle is released and the spring 48 presses clamp 46 against the bottom of the freshly inserted bottle; and the counter weight W on the treadle, lifts the latter and causes engagement of the clutch-members. The operation of each cam 21 is such as to move the work-chuck, 90 while the latter and the grinding pencil are being rotated, to keep the conical end of the pencil and the surface of the bottle-neck being ground in constant engagement; and hand wheel 40 is used for adjusting screw 30 in such wise as to bring the longitudinal axis of each chuck, or rather of the bottle held by the chuck, nearer to or farther away from the longitudinal axis of the grinding pencil, in order to adapt each set of grinding apparatus for bottle-necks of any given 95 diameter; and to regulate the contact of the work and grinding pencil.

So far as described, the operation of each of the plurality sets of grinding mechanism is identical, but it is to be noted that the cams 21 are splined on shaft 23 with their high points 25 in different positions, so that when one set of grinding apparatus is finishing its work, others will be at different stages of their respective grinding operations. Thus while the grinding operations are largely simultaneous, yet they are being completed *seriatim*, and a single attendant will suffice for one machine having a considerable number of grinding mechanisms.

It will be noted that the longitudinal axis of the work-chuck, in the present form of my invention, is at an angle of 51° to the horizontal plane of the reciprocation of the tool spindle, and that the longitudinal axis of the latter is at an angle of 11° to said horizontal plane of reciprocation. Consequently the conical end of the grinding pencil is maintained as its grinding surface is

worn away. In other forms of my invention, the said angles may be varied to suit other conditions.

A leading object of this invention is to produce a practically efficient machine for grinding glass surfaces whereby interchangeable, ground, glass bottle-necks and ground, glass stoppers therefor may be manufactured in large quantities.

Both the work-chuck and tool spindle may be rotated or only one of them rotated. In general practice the tool spindle is always rotated; but in the grinding of stopper seats, both will ordinarily be rotated and (Fig. 8) the cams 21 are formed with an idle portion α which will hold the bottle-neck so that the grinding pencil is not in engagement with its surface, and at which time one bottle may be removed and another be placed in the chuck for grinding. Each cam also has a feed portion α^1 , during the engagement of which, by the cam-roll 26, the work-chuck and tool spindle are brought into grinding relations, the rotating and reciprocating pencil grinding down the surface of the inside of the bottle-neck to a pre-determined extent; the cam also has an idle portion α^2 which effects the holding of the bottle in grinding position without feeding up to the pencil, so that the pencil will be permitted to finish and smooth off the ground surface. The cam also is provided with a quick acting return portion α^3 , the effect of which is to withdraw the bottle-neck from the pencil and bring it into idle position for removal through the slots 45. The feed portion α^1 feeds the work-chuck into grinding contact with the pencil and keeps pushing the glass against the pencil until the highest point of the cam is reached, where the portion α^2 becomes effective. During the time in which the roll 26 is working on cam portion α^2 , the pencil should be simultaneously rotated and traversed or moved endwise. When the traversing movement is completed, the roll 26 is still on a portion of α^2 , and while the roll is on this portion the feeding movement is suspended, the traversing and rotative movements of the tool being continued until the roll 26 runs on the portion α^3 . The traversing movement of the pencil during the time roll 26 is on portion α^2 comprises a considerable number of to-and-fro movements of the working surface of the pencil across a glass surface to be ground; and these repeated to-and-fro movements result in the smoothing down of the ground surface formed while roll 26 is on the cam portion α^2 . The last part of portion α^2 is so formed as to greatly reduce the amount of material during each traverse, thereby beginning the final smoothing or finishing operation. The actual curvature of the cam-groove 24 is indicated in Figs. 1, 3, 4 and 5, and the diagrammatic Fig. 8 further illus-

trates the character of the movements obtained from the cam-groove 24 and cam-wheel 26.

My invention may be embodied in forms other than shown, if so desired.

What I claim is:—

1. In a grinding machine, the combination of a work-chuck and a tool spindle mounted with their longitudinal axes at an angle one to the other; means for effecting a relative rotary movement of the chuck and spindle one to the other; means for effecting a relative traversing movement of the chuck and spindle one to the other; means for effecting a relative feeding movement of the chuck and spindle one to the other; and means for arresting the feeding movement during said relative reciprocating movement.

2. In a grinding machine, the combination of a plurality of work-chucks and tool spindles arranged in sets on a main frame with the longitudinal axes of the chucks and spindles at an angle one to the other; means for effecting a relative rotary movement one to the other of the chucks and spindles in each set; means for effecting a relative traversing movement one to the other of the chucks and spindles in each set; means for effecting a relative feeding movement one to the other of the chucks and spindles in each set; a driving mechanism common to all the sets and including means whereby the sets complete the work *seriatim*.

3. In a grinding machine, the combination of a work-chuck and tool spindle mounted with their longitudinal axes at an angle one to the other; means for effecting a relative rotary movement one to the other of the chuck and spindle; means for effecting a relative traversing movement one to the other of the chuck and spindle; means for effecting a relative feeding movement one to the other of the chuck and spindle; means for adjusting the chuck towards and away from the longitudinal axis of the tool spindle; a work-engaging member in said chuck and formed with a surface for engagement with a previously formed chuck-engaging surface on the work and shaped to permit passage of the grinding tool without contact therewith; a slidable work clamp in the chuck; means for retracting it from the work and means for causing it to engage the work and to hold the same against said work-engaging member.

4. In a grinding machine, the combination with a work-chuck and tool-spindle mounted with their longitudinal axes angularly disposed one to the other; of a work-chuck support movable in a path at an angle to the longitudinal axis of the work-chuck, and means for moving said support.

5. In a grinding machine, the combination with a work-chuck and tool-spindle mounted with their longitudinal axes at an angle one

to the other, of a slide carrying the tool-spindle; means for reciprocating said slide; a work-chuck support movable at an angle to the longitudinal axes of the work-chuck, 5 and means for moving said support.

6. In a grinding machine, the combination of a work-chuck; a tool-spindle; a grinding tool carried thereby; means for effecting working relations of the chuck and grinding 10 tool; and means for actuating the chuck to bring it successively into, with reference to work in the chuck, an idle position; a grinding position; a position for grinding without feeding; and its return idle position; 15 means for effecting a relative rotary movement of the chuck and spindle one to the other; means for reciprocating the tool-spindle; and means for effecting a feed movement of the work-chuck.
7. In a machine for spirally grinding interchangeable, spirally ground glass bottle-necks and glass stoppers therefor, and other articles, the combination of a plurality of work-holders; a plurality of grinding tools; 20 the work-holders and grinding tools coöperating in pairs; and automatic mechanism for successively throwing each of said pairs out of operation.

8. The combination of a work-holder; a

grinding tool holder; a grinding tool; means 30 for effecting a rotatable movement of said work-holder and tool, one in relation to the other; means for traversing the tool and work, one in relation to the other, during 35 said rotative movement, in a path parallel to the surface of the work to be ground at the line of contact between the working face of the tool and the work; and a mechanism comprising a succession of operative parts, one for holding said holders out of their 40 grinding position; a second for moving said holders into their grinding position; a third for holding said holders stationary in their grinding position; and a fourth for moving said holders out of their grinding position. 45

9. The combination of a tool-holder; a work-holder; means for effecting relative rotary movement of said holders; a reciprocating carrier for said work-holder; means for moving said carrier; and means for adjusting said work-holder.

In testimony whereof I have affixed my signature in presence of two witnesses.

CONRAD M. CONRADSON.
